Specification of Letters Patent.

REISSUED

Patented Dec. 7, 1915.

Application filed June 9, 1908. Serial No. 437,502.

To all whom it may concern:

Be it known that I, ALBERT V. T. DAY, a citizen of the United States, residing at New Rochelle, in the county of Westchester 5 and State of New York, have invented a certain new and useful Improvement in Railway-Traffic-Controlling Apparatus, of which the following is a specification, reference being had therein to the accompanying 10 drawings, forming part thereof.

My invention relates broadly to electric systems for controlling railway trains by means of signals, automatic stop mechanism, or other devices located upon the train itself, and the object of the invention is to produce a system of this kind which shall be simple in construction and reliable in operation.

One novel feature of the invention is the 20 means by which the electric communication is maintained between the fixed portion of the apparatus and the moving portion carried by the car or train. In the illustrated 25 form of my invention this means is embodied in the track rails, and as to this embodiment of the means for maintaining communication between the fixed portions of the apparatus and the moving portions carried by the car or train, my invention consists broadly in electrically responsive signaling or traffic-controlling apparatus carried on the train and connected with the 30 train wheels in such a manner that the electric current which governs this train apparatus 35 may be conveyed to and from the train by means of the track rails only, thus dispensing with an extra contact conductor, the track rails being included in the circuit which supplies controlling current to the 40 train apparatus in such a manner that, in tracing this circuit, the current will flow to the train by way of one or more track rails and will then flow through a conductor comprised in the train apparatus and thence 45 through one or more of the track rails away from the train. That is to say, in lieu of employing one or more track rails as one conductive lead to the train apparatus and employing an extra contact conductor as the 50 other lead, my invention broadly contemplates the utilization of the track rails as both leads. However, my invention in its broadest aspect is not limited to the employment of the track rails as conductors for

conveying controlling current to the train 55 apparatus, and whether or not the track rails are thus employed, my invention broadly comprehends, as a means for maintaining communication with the train apparatus, the utilization of the difference in potential between different points on a fixed conductor through which a current of electricity is flowing, the train being provided with two contact members engaging the conductor at two points, and with apparatus 60 connected across these contact members and responsive to the flow of current due to the difference in potential between the two points. However, I preferably utilize the track rails, or one of them, as the fixed conductor, and for the contact members I preferably utilize two car wheels when one rail is employed and two pairs of car wheels when two rails are employed, the said wheels or pairs of wheels, being preferably one in 65 advance of the other, and still more preferably being the foremost and rearmost on the car or train. When an alternating or periodic current is transmitted along the rails extending between the two wheels or 70 two pairs of wheels, the difference in potential between the points engaged by these wheels, due to the impedance of the rails, causes a flow of current through a conductor, preferably of low impedance, connecting the axles of the wheels; and this current may be utilized directly or inductively 75 to actuate a signal on the train, such as a sensitive audible signal for instance, or may be inductively or directly employed to actuate a sensitive relay carried by the train and 80 controlling a cab signal, automatic stop mechanism, or other traffic-controlling means. When I thus employ the track rails and car wheels in a circuit to control a signal or other traffic-controlling device carried on a car, my invention will preferably be embodied in an arrangement whereby this use of the track rails will not interfere with 85 using them as conductors in track circuits which control block signals; and my invention broadly comprehends such an arrangement and adaptation of the track rails.

I will now describe the embodiment of my invention illustrated in the accompanying drawing, and will thereafter point out the invention in claims.

The drawing is a diagram of a traffic-con-

trolling system embodying the invention, as applied to the west-bound track of a double-track railroad. The east-bound track and the apparatus connected therewith are not 5 shown, as they are in all respects similar.

Three signal stations are shown, designated, respectively, as A, B and C, and similar parts of the apparatus at the several stations are designated by similar reference 10 numbers, the numbers being followed, wherever necessary in the following description, by letters to indicate at which station the parts in question are located.

In the illustrated embodiment of the invention the track rails 1 are continuously 15 conductive and are utilized as the fixed conductor above referred to, while the wheels of the train are utilized as contact members. A train or car is illustrated in block A—B. 20 The forward pair of wheels 2 and the rear wheels 3 may be the forward and rear wheels of a single car, or the forward and rear wheels of a train of cars. These forward and rear wheels are connected by a conductor 4 preferably of low impedance, and 25 whenever a current is transmitted through the rails 1 extending between the two pairs of wheels, a portion of the current is diverted through the conductor 4, owing to the difference of potential between the 30 wheels 2 and 3 due to the impedance of the rails between their points of contact. In the illustrated system alternating current is transmitted through the rails, and the conductor 4 is used inductively, as the primary of a transformer, of which the secondary 35 5 is connected with a relay 6 and a telephone receiver 37, both carried by the train. A condenser 7 is interposed in the relay 40 circuit, and its capacity is adjusted relative to the inductance of the relay so as to establish resonance of the circuit for that particular frequency of current which comes from the signaling generator 14. In 45 other words, the condenser is adjusted relative to the inductance of the relay so as to tune the circuit to the frequency of the signal current. This permits the use of the rails as conductors for alternating traction 50 current in an electric railway, provided the frequency of the traction current is substantially different from that of the signal current, since the resonance of the relay circuit makes it selectively responsive to the 55 current of that particular frequency with which it is in resonance. Also, so long as the traction current is substantially different from the signaling current, the sound produced by the signaling current in the 60 telephone receiver will be readily distinguishable from the sound produced by the traction current.

The train relay 6 controls a contact finger 8 in circuit with a cab signal 9 and a signal battery 10. So long as the relay is en-

ergized the signal circuit is closed and the signal 9 is maintained at safety position by current from battery 10; but when the signal current flowing from the rails through the conductor 4 is interrupted and the relay 70 is deenergized, the contact finger opens the signal circuit and the signal moves, in obedience to its normal bias, to danger position. Also, while the signal current flows through the conductor 4, it will produce in the telephone receiver the characteristic sound which constitutes a clear signal, but when the current is discontinued the sound is discontinued in consequence, to give a danger 75 signal.

The train apparatus above described may be used, as illustrated, in connection with a block signal system of the type in which the signals are controlled by track relays connected with inductive track coils, the track 80 rails being normally energized by an alternating current. In the drawing the continuously-conductive track rails 1 are connected at the ends of the blocks by heavy cross-bonds 11 of negligible impedance, and 85 at or near the middle of each block the rails are connected with the secondary terminals of a transformer 12. The transformer is energized by connection with transmission wires 13 fed by an alternating current generator 14. Each block constitutes a divided 90 track circuit, and the alternating current passes from one terminal of the transformer along the rail connected therewith to both ends of the block, thence through the cross-bonds 11 to the other rail, and back through 95 that rail to the other terminal of the transformer. This current normally energizes inductive coils 15 and 16 located within and close to the rails at the ends of the block, 100 and these coils energize relays 17 and 18 controlling the signal circuits.

The signal relays are of the polarized alternating-current type, having field magnets constantly energized, through feed wires 19 and 20, by transformers 21 connected with the transmission wires 13. Each relay has a pivoted armature 22 provided with a coil connected with one of the track coils. Each armature has a contact finger 110 26 or 28 by which the line-circuit of the signal is controlled, and so long as both the field magnet and the armature coil are energized by alternating currents of the same frequency and proper phase relation, the 115 contact finger is maintained in contact with the coöperating fixed contact; but when the armature coil is deenergized, or energized by current of a phase which is opposite to that required to close the relay contacts, 120 then the contact finger falls and opens the line-circuit of the signal.

The transformers 12 of adjacent blocks are similarly connected to track rails; that is to say, while one transformer is delivering 125

positive current to the rail 1 uppermost in the diagram, the transformers of the adjacent blocks are also delivering positive current to that rail. As a result of this mode of connection, the track coil at the end of one block cannot be effectively energized by current from the transformer of the adjacent block, in the event of an accidental break in the cross-bond which normally limits the current of each transformer to its own particular block. For example, suppose the bond 11^B is broken, and current flows from the transformer 12 of block B-C rearward through the track rails and through the front wheels and axle of a train just in rear of the track coil 15^B. Since this current flows around the track coil 15^B in a direction opposite to normal flow of current from the transformer 12 of block A-B, the current induced in the track coil 15^B by current from the block B-C can only energize the relay armature 22^B in a direction opposite to the normal direction, thereby tending only to keep the relay contacts more positively open.

The signals 23 have a normal bias to danger position, but are held normally clear by means of any usual or suitable electrically-controlled device arranged in the line-circuit of the signal. The line-circuit by which signal 23^B is controlled passes from signal battery 24^B through line wire 25 to contact finger 26 of relay 17^C, through the contact finger and its fixed contact to line wire 27, back to station B, through fixed contact and contact fingers 28 of relay 18^B, thence through wire 29, to signal 23^B, and thence back to the battery.

So long as the track coils 15 and 16 are energized at both ends of the block by the inductive action of the track circuit, the foregoing line-circuit of the signal 23^B remains closed and this signal at the entrance end of the block stands clear. As soon, however, as a train enters any portion of the block the wheels, by bridging the rails between transformer 12 and one of the track coils, short-circuit one or both of the track coils, and the signal circuit is consequently opened by one of the relays. The signal then goes to danger and remains so until the train leaves the block.

The current from transformer 12, since it flows in opposite directions in the two rails at every point in the block, has no effect on the train signal apparatus, but the latter is controlled by another current flowing in the same direction through the two rails as parallel conductors. This train-signal current is controlled by the block signal apparatus, being automatically interrupted in a block by the same operation which places in danger position the signal at the entrance to the next block in advance.

To control the train-signal current two

controllers, 30 and 31, are connected mechanically with each semaphore 23, or with the mechanism which actuates the semaphores, the contact fingers being thereby actuated in conjunction with the semaphore. 70 These circuit controllers are connected in circuit with the transformers 21 and the track rails and the line wires 33 so that when they are in proper position current from the transformer 21 passes through the track 75 rails from one station to another. In order to economize the electric energy, the contact fingers 30 and 31 are arranged to keep these circuits normally open, but upon the entrance of a train into a block the circuit in 80 that block is closed, provided the block ahead is clear.

In block A-B of the drawing the train has short-circuited relays 17^B and 18^A, thereby opening the line-circuit through fixed 85 track signal 23^A, and the signal has moved to danger position behind the train. Circuit controller 31^A is thereby moved into engagement with its fixed contact, and the circuit is closed to energize the rails in block 90 A-B for the purpose of clearing visual train signal 9 and actuating the audible train signal 37. This circuit is as follows: from feed wire 19^B, through wire 32 to circuit controller 30 (which engages its fixed 95 contact so long as the block B-C next ahead is clear), thence through line wire 33 to circuit controller 31 and its fixed contact, and thence through wire 34 to the rail uppermost in the diagram at the point where 100 the cross-bond 11^A is located. From this cross-bond the current flows through the two rails equally to cross-bond 11^B, and thence to the wire 35 connected with the track rail lowermost in the diagram at the point where 105 the cross-bond 11^B is located, and through wire 35 to feed wire 20^B. So long as the track signal 23^B ahead of the train remains clear and the signal behind is set at danger, the block occupied by the train is thus energized to maintain the train signals clear. 110

If the block ahead of the train be occupied, the circuit above described is held open by the action of the signal at the entrance to that block. If, for example, block B-C 115 be occupied, signal 23^B, having risen to danger position, holds circuit controller 30^B in open-circuit position and thus the closing of circuit controller 31^A does not complete the circuit through block A-B and the train 120 signals are not cleared. The train signals thus act as distant signals, for, immediately upon the entrance of the train into a block, the position or sound of the visual or audible train signal indicates the position of the 125 fixed block signal at the entrance of the block ahead; and it is therefore unnecessary to provide distant signals on the fixed signal posts beside the track.

The train-signal current, being in this em- 130

bodiment of my invention derived from the same source as the block signal current, it has the same frequency as the block signal current in the track rails, and, therefore, in order that the former may not have any action on the relays governed by the inductive track coils, it is necessary to divide the train-signal current equally between the two rails, so that its inductive action on the opposite sides of the track coils may be balanced and neutralized. For this purpose the wires 34 and 35 are connected at opposite ends of the cross-bonds 11 and these cross-bonds are of such negligible impedance that the track portion of the circuit for the train-signal current includes both rails equally, so that the currents in the two rails are equalized.

The transformers 21 are all connected with the track rails so as to deliver thereto currents having the same phase and instantaneous polarity as the currents from the transformers 12. That is to say, while the transformers 12 are delivering positive current to the rail uppermost in the diagram, this rail is also receiving positive current from each transformer 21 which happens to be in closed connection with the rails by way of the wires 19 and 32, contacts 30, line wire 33, contacts 31, and wire 34. This mode of connection insures that, in the event of a broken cross-bond or rail, or both, the relay controlled by the track coil at one end of a block shall not be effectually energized by the train-signal current flowing through the adjacent block. For example, suppose that the cross-bond 11^B is broken. Current from the wire 34^B will then flow rearward along the right rail (uppermost in the diagram) to the front wheels and axle of an approaching train and thence to the left rail and thence forward along the left rail, thus passing around the coil 15^B. If the right rail is concurrently broken in advance of the cross-bond 11^B, all the current from the wire 34^B will thus flow around the coil 15^B. But in either case, the current thus flowing around the coil 15^B will energize the relay armature 22^B in a direction opposite to normal flow of current around the track coil from the transformer 12 of the block A—B. Also, under other conditions, as, for example, when a break occurs in one rail, the train-circuit current may be transmitted through one rail only so as to affect the inductive track coils of the same block through which the train current is intended to flow; but under such conditions the operation of the system is still such as to give a danger indication at the entrance to that block. Suppose, for example, that the train has reached a point in the block B—C between the transformer 12 and the signal 23^B, and suppose that one rail is broken between that signal and the train. The track coil

16^B should now be deenergized and its corresponding relay 18^B should open the line-circuit through signal 23^B and that signal should remain in danger position. With the signal 23^B in this danger position, the circuit controller 31^B will close the circuit through block B—C for the train-signal current from transformer 21^C, and this train-signal current will flow through the unbroken rail. This current, being unbalanced by corresponding current in the broken rail, will tend to energize the track coil, and the track coil will deliver current to the relay 18^B, which will either tend to close the contacts controlled by the relay, or will tend to open such contacts, according to the phase or instantaneous direction of current in the armature of the relay relative to the current in its field magnet. This relative phase or instantaneous direction depends upon which track rail is broken and which one is energizing the track coil. But we may suppose that the rail uppermost in the diagram is broken, and current for operating the train-carried signals in the block B—C flows wholly through the lowermost rail, in which event it will energize the track coil 16^B in the proper direction to close its contacts controlled by the relay 18^B. Thus the line-circuit of the signal 23^B is completed, even with the train in the rear half of the block, but as the signal starts to move to clear position and before it can move an appreciable degree, the contacts 31^B are opened, thus opening the circuit for the train-signal current, so that the relay 18^B is again deenergized. The signal thereby has an inappreciable chattering or oscillating action, while remaining at or substantially at danger position, and a clear indication cannot be given in spite of the unbalanced flow of train-signal current in the unbroken rail.

It will be apparent that the method of operating the train signal or other controlling device carried by the train may be used in connection with any traffic-controlling system arranged to suitably control the current in the rails, and it is obvious that, although the track rails and the train wheels are preferably used as the fixed conductor and the contact members, independent means may be used instead. Alternating or periodic current is preferably used where the rails serve as the conductor, since this results in a substantial difference of potential in the contact members owing to the impedance of the iron rails; but a constant current may be used in a fixed conductor having sufficient ohmic resistance to afford the necessary difference in potential. A simple type of train relay is shown for convenience in illustration, but in practice a more sensitive relay, of any usual or suitable form, may be employed to render the apparatus

responsive to a slight difference of potential in the contact members. In general, it is obvious that various modifications may be made in the embodiment of the invention hereinbefore described and illustrated in the accompanying drawing, within the nature of the invention and the scope of the following claims.

I claim:

- 10 1. An electric traffic-controlling system comprising, in combination with stationary traffic-controlling means and a car or train having a plurality of contact members, a fixed conductor engaged by said contact members, means dependent on the condition of the stationary traffic controlling means for electrically energizing the conductor, and car or train controlling means carried by the car or train and responsive to the difference in potential of the contact members.
- 20 2. An electric traffic-controlling system comprising, in combination with a car or train having a plurality of contact members, a fixed conductor engaged by said contact members, means for energizing the conductor with a periodic current, and car or train controlling means carried by the car or train and responsive to the difference in potential of the contact members.
- 30 3. An electric traffic-controlling system comprising, in combination with a car or train having two contact members, a fixed conductor engaged by said contact members, means for energizing the conductor with a periodic current, a transformer carried by the car or train and having a primary conductor connected with said contact members, and electric car or train controlling means connected with the secondary winding of the transformer.
- 40 4. An electric traffic-controlling system comprising, in combination with track rails and a car or train provided with two contact members engaging one of the rails, stationary traffic-controlling means, means dependent upon the stationary traffic-controlling means for electrically energizing said rail, and electric car or train controlling means carried by the car or train and responsive to the difference in potential of the contact members.
- 50 5. An electric traffic-controlling system comprising track rails, means for transmitting a current through the two rails in parallel, a car or train having a plurality of contact members engaging the rails at points of different potential, and electric car or train controlling means responsive to the difference in potential of the contact members.
- 60 6. An electric traffic-controlling system comprising, in combination with track rails and a car or train, means for transmitting a current through the two rails in parallel, and electric car or train controlling means

carried by the car or train and responsive to the difference in potential between the train wheels engaging said rails.

7. An electric traffic-controlling system comprising, in combination with a car or train and the track rails, means for transmitting a current through the two rails in parallel, electrically controllable traffic-controlling apparatus carried by the car or train and arranged to receive controlling electrical energy from a difference of potential between two wheels of the car or train, and a traffic-controlling track circuit in control of the traffic-controlling apparatus and including the track rails leading to the said two wheels as the sole conductors employed to lead traffic-controlling current to the car or train, whereby an extra contact conductor is rendered unnecessary.

8. An electric signaling system comprising, in combination with a car or train and the track rails, means for transmitting a periodic current through the two rails in parallel, electrically responsive signaling apparatus carried by the car or train and arranged to receive controlling electrical energy from a difference of potential between two wheels of the car or train, and a signal-controlling track circuit in control of the signaling apparatus and including the track rails leading to the said two wheels as the sole conductors employed to lead signal-controlling current to the car or train, whereby an extra contact conductor is rendered unnecessary.

9. An electric traffic-controlling system comprising, in combination with track rails and a car or train, means for transmitting a periodic current through the two rails in parallel, and electric train or car controlling means carried by the car or train and connected with two wheels thereof, one in advance of the other.

10. An electric traffic-controlling system comprising, in combination with track rails and a car or train, means for transmitting a periodic current through the two rails in parallel, and electric car or train controlling means carried by the car or train and comprising a transformer of which the primary conductor is connected with two wheels of the train one in advance of the other, and electrically-responsive apparatus connected with the secondary winding of the transformer.

11. An electric traffic-controlling system comprising, in combination with stationary traffic-controlling means and track rails and a car or train having a plurality of contact members engaging one of the rails, means dependent on the stationary traffic-controlling means for transmitting a periodic current through said rail, and electric car or train controlling apparatus carried by the car or train and responsive to the difference in potential of the contact members.

in potential of the contact members, said apparatus being in resonance with the source of current in the rail.

12. An electric traffic-controlling system comprising, in combination with a car or train having a plurality of contact members, stationary traffic-controlling means, car or train controlling means carried by the car or train, and means for connecting said stationary traffic-controlling means and car or train controlling means comprising a fixed conductor and means for producing a flow of current therein, said conductor being engaged by the contact members at points of different potential.

13. An electric traffic-controlling system comprising, in combination with track rails and a car or train having two contact members engaging one of the rails, stationary signals, means controlled conjointly with said signals for producing a current in said rail, and car or train controlling means carried by the train and responsive to the difference in potential of the contact members.

14. An electric traffic-controlling system comprising, in combination with track rails, a stationary signal, means operating to produce a periodic current through the two rails in parallel when the signal is clear in advance of a car or train, and car or train controlling means carried by the car or train and connected with two wheels thereof, one in advance of the other, the train-controlling means being responsive to difference in potential of the said wheels.

15. An electric traffic-controlling system comprising, in combination with track rails, and cross-bonds constituting track circuits, stationary traffic-controlling means operated by said track circuits, a car or train having contact members engaging the rails at points of different potential, electric car

or train controlling means carried by the car or train and responsive to the difference in potential of said contact members, and means for transmitting periodic current through the rails in parallel to operate the car or train controlling means.

16. An electric traffic-controlling system comprising, in combination with continuously conductive track rails and cross-bonds of negligible impedance, a train or car provided with electric train or car controlling means responsive to the difference in potential of two wheels of the train or car, one in advance of the other, and means for transmitting a current through the rails to operate the train-controlling means, said current-transmitting means being connected with the rails at two cross-bonds so that the intervening portions of the two rails constitute, with the bonds, paths of equal impedance for the current.

17. An electric traffic-controlling system comprising a contact conductor extending along a given section of the railway, a car or train, contact devices carried thereby and arranged to engage the contact conductor at different points, traffic-controlling apparatus on the car or train connected with the contact devices and responsive to potential difference between them, means for transmitting a current through the contact conductor, and means for controlling said current by the traffic-governing conditions of the track in advance of the given section of the track.

In testimony whereof I have affixed my signature in presence of two witnesses.
